UNITED STATES PATENT OFFICE

JOHN M. BOSCARDIN, OF CANAAN, CONNECTICUT

DEVICE FOR RAISING SUBMERGED OBJECTS

Application filed June 20, 1928. Serial No. 286,892.

This invention relates to improvements in devices for raising submerged objects such as ships.

One of the objects of this invention is to provide an efficient apparatus for grappling and raising vessels which have been submerged at sea and which is simple of construction and easily operated and controlled from a salvaging ship or other center of operation.

A purpose of this invention is to provide a device for raising submerged objects, the device comprising a hollow receptacle, or a plurality of them, adapted to be supplied with sufficient liquid to submerge it in the proximity of the object to be raised, and having adjustably suspended from the hollow receptacle a plurality of grappling cables, operable means being attached to the hollow receptacle for bringing the grappling cables into desired position in contact with the object to be raised.

A further object of this invention is to provide a device for raising sunken ships and the like, having means operable from a salvaging ship or other center of operation for firmly bringing grappling hooks and cables suspended from the device into close contact with the submerged object.

Other objects of this invention will appear from the following detailed description of the device and as disclosed in the two sheets of drawings which are herewith made a part of this application.

In the drawings—

Figure 1 illustrates a perspective view of the device for raising submerged objects in assembled relationship with a salvaging vessel.

Figure 2 illustrates a side elevational view of the submerged object raising device disclosing the grappling cables and means for bringing them into firm contact with the side of the submerged object.

Figure 3 illustrates a plan view of Figure 2 disclosing the grappling members in contact with the object to be raised.

Figure 4 represents a vertical section view 50 of the hollow receptacle disclosing the vari-

ous grappling cables and adjustable weights connected thereto.

Figure 5 represents a vertical sectional view of Figure 4 taken along line 5—5.

Figure 6 illustrates a plan view of Figure 5 taken along line 6—6.

Figure 7 represents a perspective view of the cable belt member adapted to the purpose of supporting the weights in adjustable relationship to the hollow receptacle.

In the device for raising submerged objects, according to this invention, it is preferred that numeral 1 designates a salvaging ship or other center of operation adapted for the purpose of cooperating in adjusting the hollow receptacle 2, which may be made of cast iron or other suitable material, in proper position relative to a submerged object such as a sunken ship 3.

In the process of raising the ship 3, a plurality of the hollow receptacles 2 may be used if it is considered necessary. However, for the purpose of this application the following description will cover but one of the devices designated by the numeral 2.

The general shape of the container or hollow receptacle 2 may be of any desirable configuration, but preferably oval in form, as disclosed in the drawings. The construction of this container 2 must be along the lines of maximum strength in order to withstand the tremendous pressures existing in deep sea work.

The air capacity of the container 2 should be sufficient for the raising of the object.

Integrally fastened or otherwise to the periphery of the receptacle 2 is a band member 4, made of cast iron or other suitable material and adapted to have integrally formed therewith or securely fastened thereto a plurality of lug members 5, having openings therein for loosely receiving cable portions 6, which are adapted to extend downwardly from the receptacle 2 a suitable distance, and having attached at the ends thereof a plurality of grappling members 7, which may be provided with hooks 8, or other means for secure attachment to the side of the object 3 during the raising thereof.

In normal position the cables 6 and grappling members 7 will hang suspended from the container 2, and intermediate between the points of suspension 5 and the grappling members 7, along the cable elements 6 are adapted to be located a plurality of clamping members 9, which securely hold the cable portions 6 in operable relationship, and at the same time function to act as a stop for the belt cable 10, which is adjustably and operably mounted on the receptacle 2, as clearly disclosed in the figures of drawing 1 and 4, wherein the belt cable 10 is provided with a pair of weights 11 and 12, suspended by means of cables 13 and 14, from ratchet elements 15 and 16, which are mounted upon brackets 17 and 18, extending from the receptacle 2. A cable 19, having upwardly extending end portions 20 and 21 for operably holding dog elements 22 and 23, extends through a suitable fitting 24, upwardly to the salvaging ship 1, where it may be operated by means of a windlass or other suitable device.

The dog members 22 and 23 operate in connection with the ratchet elements 15 and 16, the cable portions 13 and 14, supporting the weights 11 and 12, function to wind upon drum members 25, as clearly disclosed in Figure 4, wherein the weights 11 and 12 are disclosed in normal uplifted position previous to the releasing of the dog elements 22 and 23, when the weights would drop, thereby causing the cable belt member 10 to slide along the cables 6 until striking the clamping members 9, when the weights 11 and 12 would continue their downward movement, thereby forcing the cables 6 and the grappling members 7 inward toward the object 3 to be raised.

The top of the container 2 is preferably fitted with a cap member 26, securely fastened to the main body portion 2 by means of rivets 27, or otherwise.

A lug portion 28, integrally formed from the cap 26, is provided having an opening 45 therein for receiving a chain or cable member 29, which extends from the top of the receptacle 2 to the salvaging ship 1, where it may be operably connected with a windlass.

The hollow receptacle 2 is provided with a plurality of guide lines 30 and 31, which preferably are attached to the band member 4 at one end and extend into the salvaging ship 1, where they are operated by hand or otherwise, as may be desired, for the purpose of guiding the receptacle 2 and holding it firmly in position.

The receptacle 2 in this invention may be supplied with a suitable amount of liquid and air in the usual manner, such as liquid and air pipe lines extending from the receptacle 2 to proper pumps located in the salvaging ship. An air line 32 extending from a suitable fitting 33 leads upward into the salvaging ship 1, as clearly disclosed in Figure 1, and a pipe line 34 is shown extending from

the receptacle 2 upward into the ship 1. The lower portion of the pipe line 34 may extend inwardly of the receptacle 2 a sufficient distance for assuring the complete pumping of the liquid therefrom, if desired, by means of a pump located in the salvaging ship 1.

Obviously, the location of the air and liquid pipe lines, so far as this invention is concerned, has no appreciable effect upon the spirit thereof. It may be desirable under some circumstances to have the container filled with approximately two-thirds water and one-third compressed air, the proportions of which are adapted to be regulated from the salvaging ship 1.

In operation this invention provides an efficient means for raising a submerged object such as a vessel which has been sunk in deep waters. The container 2 is supplied with a suitable amount of liquid and air, and positioned at a desired point above the submerged object, as clearly shown in Figure 1, after which the cable 19 is operated from the salvaging ship 1, and the weights 11 and 12 are allowed to move downward thereby forcing the grappling members 7 into close contact with the submerged object 3 by means of the belt cable 10. The proportions of air and liquid within the container 2 may then be easily regulated, for instance, the liquid may be entirely removed by pumping, and compressed air substituted, or certain proportions of air and liquid admitted in the container, depending upon the requirements of the situation.

In case the submerged object is firmly held in the mud, or otherwise, it may be found desirable to haul in on the chain 29 by proceeding ahead with the salvaging ship 1, which will very likely tend to lessen the hold of the submerged object in the mud.

It will be understood that many changes and modifications may be made in the form of embodiment of the invention within the scope of the following claims without departing from the spirit of the invention.

What I claim is:

1. In a device of the character described, a container, a band element connected thereto, a plurality of cables supported by the band member, grappling members attached to the cables, means adjustably connected with the container constricting the cables and grappling members.

2. In a device of the character described, a container, a band element connected thereto, a plurality of cables supported by the band member, grappling members attached to the cables, means adjustably connected with the container constricting the cables and grappling members, guiding means extending from the container for locating the container in position.

3. In a device of the character described, a container, a band element connected there-

to, a plurality of cables supported by the band member, grappling members attached to the cables, means adjustably connected with the container constricting the cables and grappling members, guiding means extending from the container for locating the container in position, hauling means extending from the container.

4. In a device of the character described, 10 a container, a band element connected thereto, a plurality of cables supported by the band member, grappling members attached to the cables, means adjustably connected with the container constricting the cables and 15 grappling members, guiding means extending from the container for locating the container in position, hauling means extending from the container, liquid and air supply means extending into the container.
- 20 5. In a device of the character described, a container, a band element connected thereto, a plurality of cables supported by the band member, grappling members attached to the cables, a cable belt operably supported 25 by the container, a plurality of weights fastened thereto, means for allowing the weights to drop thereby forcing the cable belt into constricted relationship with the cables and the grappling members.

30 In testimony whereof I affix my signature.
JOHN M. BOSCARDIN.
